WINTHROP K. HOWE, OF ROCHESTER, NEW YORK, ASSIGNOR TO GENERAL RAILWAY SIGNAL COMPANY, OF ROCHESTER, NEW YORK

TRAIN-CONTROL SYSTEM

Application filed March 12, 1927. Serial No. 174,831.

This invention relates in general to a train control system, and has more particular reference to an automatic inductive train control system of the alternating current type, 5 including acknowledging and reset means.

In train control systems of the type referred to, it is usual to have spaced trackway inductors controlled in accordance with the traffic conditions and arranged to inductively influence a normally energized, alternating current, car-carried receiver, to cause such receiver to produce a train restricting influence, such as a brake application, or the like, unless prevented by the proper operation of 15 an acknowledging device. If the train restricting influence be exerted it is then generally necessary to manually operate a reset device to restore the various parts to normal. In such systems the car-carried device usually 20 comprises a main relay, with its energizing circuit tuned to oscillate most freely at the frequency of the current employed, so that after being de-energized, if its armature has assumed its retracted position, the energizing 25 circuit is thereby detuned, and removal of the trackway influence does not result in attraction of the armature of such relay, it being necessary, in some independent manner, to restore the armature to attracted position. 30 It is well recognized, of course, that movement of a relatively large mass of iron, such as an armature, will exert a large effect on the tuning of an associated circuit.

With the above and other considerations 35 in mind, it is proposed, in accordance with this invention, to provide acknowledging and reset means for respectively preventing, for a temporary period, the dropaway of the main relay armature, upon de-energization of 40 such relay, and for restoring the dropped away armature to attracted position.

More specifically, it is proposed to provide 45 an electro-magnet associated with the armature of the main relay to exert an attraction thereon when energized, and to have manually operable acknowledging and reset contactors operable to respectively energize the electro-magnet through a circuit including a 50 current limiting resistance, and through a circuit not including the current limiting re-

sistance, whereby, when energized by the acknowledging contactor, the electro-magnet can hold the relay armature in attracted position but cannot move it to such position, and when energized by the reset contactor it can 55 move the armature from retracted to attracted position and hold it so.

Further objects, purposes, and characteristic features, of the present invention will appear as the description progresses, reference 60 being had to the accompanying drawing, showing, solely by way of illustration, and in a wholly diagrammatic manner, one physical form which the invention can assume.

The single figure of drawing shows one 65 embodiment of the present invention as applied to a simplified type of train control system.

Referring to the drawing, a stretch of track 70 constituted by rails 1, is divided into blocks by insulating joints 2, and furnished with wayside signals 3, shown as of the semaphore type, but which may equally well be of any other desired type it being deemed unnecessary to show and describe the various signal 75 control circuits and devices. Each signal 3 is arranged to control a trackway inductor 4, at the entrance to its block in such a manner as to place the inductor in active condition under danger and caution conditions of the 80 block in question, and to place the inductor in inactive condition under clear conditions of such block. The particular means for effecting this control has not been shown or 85 described in detail, as it is deemed quite unnecessary for a full and complete understanding of the present invention, such control means being well understood by those versed in this particular art.

A receiver 5, shown in the form of an H, 90 and having two primary coils P, and two secondary coils S, is arranged to be so carried by a car, represented diagrammatically by wheels and axles 9, as to pass over the inductors 4, out of contact therewith, but in 95 inductive relation thereto. The primary coils P are connected in series with each other, with a condenser 7, and an alternating current source of electrical energy 8, preferably of a higher than commercial frequency, 100

as for example, 360 cycles per second. The condenser 7 is so chosen as to tune its circuit to oscillate most freely at the frequency of the current employed.

5 The secondary coils S are likewise connected in series with each other, with a condenser 10, and coils 11 carried on a core 12 constituting a main relay MR. The circuit including the condenser 10 is likewise tuned to the 10 frequency of the current employed, and is energized inductively by the transformer action between the primary and secondary coils on the receiver 5, as is well understood by those versed in this particular art.

15 The main relay MR has an armature 13, pivoted at 14, and biased to its retracted position by a spring 15, a projection 16 being carried by, and insulated from, the armature 13.

20 When the receiver passes over an inductor 4, in active condition, the inductor so affects the receiver as to change the distribution of flux threading the secondary coils S, so as to reduce the current flowing in the main relay coils 11, to zero, or at least sufficiently to de-energize such relay and permit the armature 13 to be rocked clockwise by spring 15.

25 In the event the inductor under consideration be inactive it can exert no appreciable influence on the receiver 5, and the main relay MR remains energized.

30 Carried by the projection 16 are two contact fingers 16¹, arranged to control the energizing circuit for a brake applying device EPV which can be of any usual or desired character, but is here shown as a normally energized electro-pneumatic device arranged when de-energized to either apply the brakes, or impose any other desired restriction on train movement. The energizing circuit for EPV is traceable from the positive side of 35 generator 28, contact finger 20 and front point of Res, contact finger 24 and front point Ack, lower contact finger 16¹ and front points of MR, the winding of EPV, upper contact finger 16¹ and front points of MR, back to the 40 negative side of generator 28.

45 Arranged adjacent the armature projection 16, is an electro-magnet 17, which when energized exerts an attracting influence on the armature 13 to either maintain it in attracted position, or to move it to, and retain it in, attracted position, depending upon the character of energization thereof.

50 The system also includes a reset device, Res, comprising a rod 18, manually operable to move contact fingers 19 and 20 to control various connections, as explained below. This reset device is arranged to be operable only when the train is stationary, as by being placed in a position accessible only from the ground, in order to avoid operation thereof during movement of the train.

55 An acknowledging device Ack is shown, and comprises a spring biased, manually operable, rod 21 arranged to operate contact

60 fingers 22, 23 and 24, the finger 24 having a retarded opening effect, due to springs 25 and a dash pot or the like 26. Included in a circuit completed by the acknowledging device, is a current limiting resistance 27.

65 The source of energy for the electromagnet 17 is shown as a direct current generator 28 directly connected to the alternator 8.

70 The operation of the system above described is as follows. Assuming that the receiver 5 passes inductively over the inductor 4 when the latter is in its inactive condition, no disturbing influence is exerted on the main relay MR and the parts remain in their normal position as shown, that is, in the position 75 and condition existing during travel under clear conditions.

75 Assuming now that the car is proceeding into a caution or danger block, under which conditions the inductor 4 in question is in its active condition, this inductor will so influence the receiver 5 as to de-energize coils 11 and thus cause a dropaway of armature 13 of main relay MR. This will de-energize the 80 brake device EPV at the contact fingers 16¹ and front contacts of the main relay and produce an automatic brake application, as explained above, the EPV device being normally energized from the source 28 through the circuit traced above, including contact 85 fingers 16¹ and front contacts of relay MR, and contact fingers 24 and 20 and front contacts of Ack and Res respectively.

90 The above brake application was incurred under the assumption that the engineman did not operate the acknowledging device Ack. In order to relieve the train from the brake application, and allow it to proceed, it is necessary to restore main relay armature 13 to attracted position in order to reenergize EPV. 95 As explained above, the circuit including coils 11 of the main relay, is a tuned circuit, which has its inductive reactance materially decreased, and becomes detuned, by the dropping away of the armature 13, and hence the 100 induced current flowing through these coils is insufficient when the circuit is detuned, to pick up the armature 13. In these circumstances, it is necessary to bring the car to a 105 full stop in order that the reset device Res can be depressed to thereby energize the electro-magnet 17 through a circuit including contact finger 20 and back contact of Res, generator 28, and contact finger 19 and back 110 contacts of Res, whereupon armature 13 is attracted to its restored position after which it is retained in such position by the induced current flowing in the now tuned circuit including coils 11. It will be noted that the 115 normal energizing circuit for EPV passes through contact finger 20 and front contact of Res so that it is necessary before the train proceeds, to restore the reset device to its normal shown position. This feature of the reset device also insures against misuse of the 120

125 reset device.

130

same, as for example, by tying it down in an attempt to avoid a brake application on passing an active inductor without acknowledging.

Under the assumed conditions, namely passage of the receiver 5 over an active inductor 4, if the engineman is alert and depresses the lever 21 of the acknowledging device *Ack*, shortly before passing over the inductor, an energizing circuit is completed for the electro-magnet 17 which includes contact finger 22 and back contact of *Ack*, source 28, contact finger 23 and back contact of *Ack*, and the limiting resistance 27. Due to the circuit just traced, including the limiting resistance 27, sufficient current flows to maintain armature 13 in attracted position, but insufficient current flows from the electro-magnet 17 to move the armature 13 to its attracted position if it has previously dropped away. This prevents the acknowledging device from being used in a reset capacity. With the armature 13 maintained in attracted position, the de-energization of coils 11 does not cause any break in the energizing circuit for EPV, and an automatic brake application is avoided.

Should the engineman attempt to defeat the purpose of the system in question, by holding down the acknowledging contactor for too long a time, or depressing it at too early a time, contact finger 24 will nevertheless open after about 15 seconds from the operation of the acknowledging device, to thereby break the normal energizing circuit for EPV at such contact finger and cause an automatic brake application.

By the system described above it will be seen that the acknowledging device is protected against misuse by having its energizing circuit for the electro-magnet 17, include the current limiting resistance 27. On the other hand, the reset device *Res* is positioned to protect it against misuse and is arranged to control an energizing circuit for the electro-magnet 17 which excludes any limiting resistance whereby to permit it to function to move the armature of the main relay from retracted to attracted position.

In order to more certainly guard against false operation of the system due to crossed wires and the like, double breaks have been provided, that is, a break in both the positive and the negative wire, in the energizing circuits for the brake applying device EPV, as at the two contact fingers 16¹, and in the circuits completed by the acknowledging and reset contactors *Ack* and *Res*, as at contact fingers 22 and 23, and contact fingers 19 and 20 respectively. In these circumstances, a single cross, as for example, a cross connecting the two wires leading to the lower contact finger 16¹, cannot operate to close a circuit such, for example, as the normal EPV circuit, when it should be open, as would possibly be the case if the circuits referred to

were made and opened at but a single wire.

The above rather specific description of one form of the invention, is given solely by way of example, and is not intended, in any manner whatsoever, in a limiting sense. Obviously, the invention can assume many different physical forms, and is susceptible of numerous modifications, and all such forms and modifications are intended to be included in this application, as come within the appended claims.

Having described my invention, I now claim:—

1. In a train control system, a normally energized alternating current car carried element controlled in accordance with traffic conditions, an electric brake applying device normally energized to hold off the brakes and controlled by the said element, and means to only temporarily suspend the control between the element and device and only when said element is energized including a manually controlled electro-magnetic means having an energizing circuit including a current limiting means.

2. In a train control system, a normally energized alternating current car-carried element controlled in accordance with traffic conditions, a brake applying device controlled by said element, means to temporarily suspend the control between the element and device including electro-magnetic means manually energizable through current limiting means, and means to suspend the control for an indefinite period including manually operable means to energize the electro-magnetic means through a circuit shunting said current limiting means.

3. In an alternating current train control system, an influence receiving device normally energized through a tuned circuit, a normally energized electric brake control means initiated upon de-energization to set the brakes and energized through a circuit controlled by said device, and means for only temporarily preventing de-energization of the brake control means by the influence receiving device including a manually controlled member having an energizing circuit including a current limiting means acting to allow said preventing only if the receiving device is not already deenergized.

4. In an alternating current train control system, an influence receiving device normally energized through a tuned circuit, a brake control means initiated upon de-energization and energized through a circuit controlled by said device, means for temporarily preventing de-energization of the brake control means by the influence receiving device including a member energized through a circuit including a current limiting means, and means for re-energizing the brake control means including a manually operable device

- for energizing said member through a circuit excluding said current limiting means.
5. In a train control system, a car-carried relay normally energized by alternating current and controlled in accordance with traffic conditions, a normally energized brake device initiated upon de-energization and having an energizing circuit including a front contact of the relay, and an electro-magnetic device, manually energizable, to respectively prevent de-energization of, and to re-energize, the brake device, through a circuit including a current limiting means, and a circuit excluding such current limiting means.
- 10 6. In a train control system, a car-carried relay normally energized by alternating current and controlled in accordance with traffic conditions, a normally energized brake device initiated upon de-energization and having an energizing circuit including a front contact of the relay, an electro-magnet, acknowledging means to energize the magnet to hold up but not pick up, the said relay, and reset means to energize the magnet to pick up and hold up the said relay.
- 15 7. In a train control system, a car-carried relay normally energized by alternating current and controlled in accordance with traffic conditions, a normally energized brake device initiated upon de-energization, and having an energizing circuit including a front contact of the relay, an electro-magnet, acknowledging means to energize the magnet, through a current limiting resistance, to hold up but not pick up, the said relay, and reset means to energize the magnet, through a circuit excluding said resistance, to pick up the said relay.
- 20 8. In a train control system, a main control relay subject to trackway influences, a brake control device normally controlled by the relay, a second device associated with the relay and affecting the control of the brake control device by the main relay, and separately controllable energizing circuits including separate manually operable switches, for the said second device permitting different amounts of current to flow through said second device to thereby vary the manner in which said second device can affect said control.
- 25 9. In a train control system, a main control relay subject to trackway influences, a brake control device normally controlled by the relay, an electro-magnetic device associated with the relay, and two manually controlled energizing circuits for the said device permitting different amounts of current to flow through the device causing, respectively, hold up only, and pick up and hold up, currents to flow through the electro-magnetic device.
- 30 10. In a train control system, a main control relay subject to trackway influences, a brake control device normally controlled by the relay, a device associated with the relay,
- an acknowledging contactor operable to energize the device with only sufficient current to hold up the armature of the control relay, and a reset contactor, operable only from the ground, to energize the device with sufficient current to pick up the armature of the control relay.
- 35 11. In a train control system, a normally energized main relay controlled in accordance with traffic conditions, a tuned energizing circuit for said relay detuned on release of the relay armature, a brake applying device controlled by said relay, a coil associated with the main relay for respectively holding up, and picking up, the main relay armature, an acknowledging energizing circuit for said coil including a current limiting member for energizing the coil to be effective to hold up but not to pick up the main relay armature, and a reset energizing circuit for said coil shunted around said current limiting member for energizing the coil to pick up the armature of said main relay.
- 40 In testimony whereof I affix my signature.
- WINTHROP K. HOWE.
